UNITED STATES PATENT OFFICE.

JOSEPH S. DUNCAN, OF CHICAGO, ILLINOIS, ASSIGNOR TO ADDRESSOGRAPH COMPANY, OF CHICAGO, ILLINOIS, A CORPORATION OF ILLINOIS.

MACHINE FOR ROLLING PRINTING-PLATES.

1,239,679.

Specification of Letters Patent. Patented Sept. 11, 1917.

Application filed August 7, 1916. Serial No. 113,665.

To all whom it may concern:

Be it known that I, JOSEPH S. DUNCAN, a citizen of the United States, residing at Chicago, in the county of Cook and State of Illinois, have invented certain new and useful Improvements in Machines for Rolling Printing-Plates, of which the following is a specification.

This invention relates to a machine for 10 rolling printing plates having characters struck up from the body of the plate.

Printing plates having characters struck up from the body of metal blanks have been made prior to my invention. These plates 15 are usually made in machines equipped with coöperating punches and dies. The faces of the printing characters when so formed are more or less curved, particularly adjacent the edges so that sharply defined impressions 20 can not be obtained therefrom. Furthermore, owing to slight inaccuracies of the punches and dies and of the operating mechanism therefor some of the characters are higher than others and the plate does not 25 present a plane surface.

It is an object of my invention to provide a machine for rapidly and effectively reducing the faces of printing characters on a printing plate to a uniform plane.

30 A further object of my invention is the provision of a machine for rolling printing plates to provide the characters thereon with sharply defined edges, whereby the printing quality of the plates is materially improved.

35 Further objects and advantages of my invention will be apparent as it is better understood by reference to the following specification when read in connection with the accompanying drawing, illustrating the preferred embodiment thereof, in which—

Figure 1 is a plan view of a machine according to my invention;

Fig. 2 is an end elevation thereof;

Fig. 3 is a section on the line 3—3 of

45 Fig. 1;

Fig. 4 is a side elevation of the machine;

Fig. 5 is a section on the line 5—5 of Fig. 3, and

Fig. 6 is a section on the line 6—6 of

50 Fig. 4.

Referring to the drawings a suitable frame 1 is provided to support the various parts of the mechanism and particularly the bed 2 (Fig. 3) upon which the printing plates 3 55 are intermittently and successively posi-

tioned by mechanism including dogs 4 (Fig. 5) pivotally mounted in reciprocating bars 6 and normally held by springs 7 in position to engage the edges of successive plates and thus advance the plates when the bars 6 are 60 reciprocated. The bars 6 are actuated by mechanism including a swinging member 8 pivotally mounted at 9 on the frame 1 and connected by a link 10 to a rocker 11 pivotally mounted at 12 on the frame 1 which is 65 in turn connected by a link 13 to the slide 14 carrying the reciprocating bars 6. The foregoing mechanism is similar in structure and mode of operation to the plate feed mechanism illustrated and described in the 70 patent to Joseph S. Duncan No. 764,660, July 12, 1904, and is a well-known structure being employed in a machine commercially known as the "Addressograph."

A member 16 is adjustably secured by 75 screws 17 to the support 15 and is provided on its under face with a plate 18 extending laterally therefrom. A carriage 19 is provided with rollers 20 engaging the upper surface of the laterally extending edges of 80 the plates 18, whereby the carriage is supported in operative position. The carriage 19 is provided with depending arms 21 in which a pressure roller 22 is journaled and an anti-friction roller 23 having flanges 24 85 is supported on the arms 21 between the pressure roller 22 and the lower face of the plate 18. The plate 18 is provided with depressions 25 adjacent one end to receive the flanges 24 and the opposite end is cut away 90 at 26, the purpose being to allow the pressure roller 22 to be lifted when the movement of the carriage 19 is completed in either direction. During the rolling operation the pressure roller 22 is spaced from the bed 2 95 a distance equal to the desired height of the characters on the plate 3 by engagement of the anti-friction roller 24 therewith and with the plate 18.

The means for actuating the carriage 19 100 comprises a shaft 27 mounted in suitable bearings 28 and provided at one end with a crank disk 29. A link 30 connects the crank disk 29 to the carriage 19. Secured to the opposite end of the shaft 27 is a disk 31 having a pawl 32 (Fig. 6) pivotally mounted at 33 on one of its faces. A spring 34 connected to a pin 35 on the pawl 32 and to a pin 36 on the disk 31 biases the pawl 32 toward a member 37 loosely mounted on the shaft 27 110

and provided with a pair of notches 38. A bevel pinion 39 is connected to and preferably formed integral with the member 37 and engages a bevel rack 40 on a segment 41 pivotally mounted at 42 on the support 15. A link 43 connects the segment 41 to the swinging member 8.

A member 44 (Fig. 6) is pivotally mounted at 45 on a lug 46 depending from an arm 47 of the support 15 and is provided at its free end with a roller 48 adapted to engage notches 49 in the periphery of the disk 31. A spring 50 connected to a pin 51 on the arm 47 and to a pin 52 on the member 44 biases the member toward the disk 31. A plate 53 secured to the member 44 is disposed in the path of a plunger 54 slidably supported in a bifurcated extension 55 of the segment 41. A spring 56, disposed between the arms of the extension 55 and engaging a pin 57 on the plunger 54 normally holds the plunger in the position indicated in Fig. 4. When the segment 41 swings on its pivot to the limit of its travel the plunger 54 resiliently engages the plate 53 to force the roller 48 into one of the notches 49 when a half revolution of the shaft 27 has been accomplished, thus positively preventing overthrow of the shaft 27.

The mode of operation of my invention will be apparent from the following brief description thereof. The printing plates 3 may be fed from a magazine (not shown) and are advanced intermittently and successively to position on the bed 2 by operating the swinging member 8, which may be a foot or hand lever, or may be connected in any suitable manner to a motor or other source of power. As the swinging member 8 is rocked to the right, viewing Fig. 4, the dogs 4 are withdrawn to engage the successive printing plates 3, leaving a printing plate upon the bed 2. Simultaneously the segment 41 is rocked on its pivot rotating the pinion 39 and consequently the member 37 which, as indicated in Fig. 6, is engaged by the pawl 32 on the disk 31. The disk 31 is consequently rotated and the shaft 27 and crank disk 29 moved through a half revolution, the carriage 19 being moved to the position indicated in Fig. 2 to the opposite end of the bed 2. The plate 3 on the bed 2 is subjected to pressure by the pressure roller 22 to reduce the characters thereon to a common plane and provide well-defined edges on the faces of the characters. Upon return of the swinging member 8 to its normal position, indicated in Fig. 4, the successive plate 3 is advanced to position on the bed 2, the carriage 19, however, remaining stationary. Upon again actuating the swinging member 8 the carriage 19 is operated in the reverse direction, subjecting the plate 3 to pressure of the pressure roller 22 with the previously described result.

The carriage 19 moves across the bed 2 in opposite directions as each successive printing plate 3 is positioned on the bed 2 and each plate is, therefore, automatically subjected to pressure to obtain the desired result. The rapidity with which the printing plates can be treated is greatly augmented by the operation described. The faces of the characters on plates so treated are disposed in a common plane and are provided with sharply defined edges so that the best results are obtained when impressions are taken from the plates. My machine is simple in construction and rapid in operation and may be operated by relatively unskilled persons.

It will be apparent that various changes may be made in the form, construction and arrangement of the parts without departing from the spirit and scope of the invention or sacrificing any of its material advantages, the form hereinbefore described being merely a preferred embodiment thereof.

I claim:

1. In a machine of the character described, the combination of a fixed bed, means for intermittently and successively positioning printing plates having characters struck up from the body thereof upon said bed, and means for automatically subjecting said plates to rolling pressure when so positioned to reduce the faces of the characters thereon to a common plane.

2. In a machine of the character described, the combination of a fixed bed, means for intermittently and successively positioning printing plates having characters struck up from the body thereof upon said bed, a roller, and means for automatically actuating said roller to subject said plates to pressure when so positioned to reduce the faces of the characters thereon to a common plane.

3. In a machine of the character described, the combination of a fixed bed, means for intermittently and successively positioning printing plates having characters struck up from the body thereof upon said bed, a roller, and means for automatically actuating said roller in opposite directions as successive plates are so positioned to reduce the faces of the characters thereon to a common plane.

4. In a machine of the character described, the combination of a bed, means for intermittently and successively positioning printing plates having characters struck up from the body thereof upon said bed, a rigid support above said bed, a carriage movable thereon, a roller supported by said carriage, and means for actuating said carriage in opposite directions across said bed when successive plates are positioned on said bed to subject said plates to pressure by said roller.

5. In a machine of the character described, the combination of a bed, means for intermittently and successively positioning printing plates having characters struck up 55
 5 from the body thereof upon said bed, a rigid support above said bed, a carriage movable thereon, a pressure roller supported on said carriage, an anti-friction roller on said carriage between said pressure roller and support, and means for actuating said carriage in opposite directions when successive plates are positioned on said bed to subject said plates to pressure by said pressure roller.
- 10 6. In a machine of the character described, the combination of a fixed bed, means for intermittently and successively positioning printing plates having characters struck up from the body thereof upon said bed, a pressure roller movable over said bed and spaced therefrom a distance equal to the desired height of the characters on said plate, and means for actuating said roller in opposite directions as successive plates are positioned above said bed including an operating member and an intermittent connection between said member and roller.
- 15 7. In a machine of the character described, the combination of a bed, means for intermittently and successively positioning printing plates having characters struck up from the body thereof upon said bed, a carriage movable over said bed, a pressure roller supported by said carriage and spaced from said bed a distance equal to the desired height of the characters on said plates, and means for actuating said carriage in opposite directions as successive plates are positioned on said bed, including a shaft, a 80
 30 crank secured thereto, a link connecting said crank and carriage, an operating member, and an intermittent connection between said operating member and shaft.
- 35 8. In a machine of the character described, the combination of a bed, means for intermittently and successively positioning printing plates bearing characters struck up from the body thereof upon said bed, a carriage movable over said bed, a pressure 85
 40 roller supported by said carriage and spaced from said bed a distance equal to the de-
- sired height of the characters on said plates, and means for actuating said carriage in opposite directions when successive plates are positioned on said bed, including a shaft, a crank secured thereto, a link connecting said crank and carriage, a member secured to said shaft and provided with a pawl, a member loose on said shaft and provided with notches adapted to be engaged by said pawl, 60
 45 a pinion loose on said shaft and connected to said last-mentioned member, a pivoted segmental rack engaging said pinion, and means for rocking said rack.
- 50 9. In a machine of the character described, the combination of a bed, means for intermittently and successively positioning printing plates bearing characters struck up from the body thereof upon said bed, a pressure roller movable over said bed and spaced therefrom a distance equal to the desired height of the characters on said plate, means for actuating said roller in opposite directions as successive plates are positioned on said bed including an operating member and an intermittent connection between said member and roller, and means for positively limiting the movement of said roller to prevent overthrow thereof.
- 55 10. In a machine of the character described, the combination of a bed, means for intermittently and successively positioning printing plates bearing characters struck up from the body thereof upon said bed, a pressure roller movable over said bed and spaced therefrom a distance equal to the desired height of the characters on said plate, means for actuating said roller in opposite directions as successive plates are positioned on said bed including a shaft, a 90
 60 crank secured to said shaft, a link operatively connecting said crank and roller, an operating member and an intermittent connection between said operating member and shaft, and means for limiting the rotation of said shaft at each successive operation thereof to prevent overthrow of said roller.
